PROCESSING APPARATUS FOR FIBER CAKES

Harry S. Drum, Abington, and William C. Dodson, Meadowbrook, Pa., assignors to Smith, Drum and Company, Philadelphia, Pa., a corporation of Pennsylvania

Application August 15, 1934, Serial No. 739,996

17 Claims. (Cl. 18—8)

The present invention relates to the manufacture of silk threads or filaments or silk staple fiber or synthetic silk, or the like and more particularly to an apparatus for use in carrying out 5 some or all of the steps in the manufacturing processes.

In the manufacture of products to which this invention relates it has heretofore been proposed to mount the annular spun fiber cake (the form 10 which the material assumes after the setting bath, passing the godet wheel, and spinning box) upon a carrier which includes means for radially spraying liquids against the inner hard compact face of the cake and then causing such liquid 15 to force its way through the cake by centrifugal action. In such prior structures the outer periphery of the cake is unprotected and is free to swell outwardly under the developed centrifugal force. As a result the rotating of the cake during 20 the treating operations causes it to assume an uneven shape, more generally that of an ellipse, with the consequent dense packing of threads at one location while at others there will be a variation due to less dense packing. The general effect 25 is non-uniformity of treatment. Furthermore confining the treating operations solely to the centrifugal flow of liquid through the hard cake makes it necessary to prolong the treatment unduly to ensure that the radial flow of liquid 30 overcomes the inherent resistance of the cake and completes each step in a thorough manner.

Some of the objects of the present invention are to provide an improved apparatus for use in the manufacture of artificial silk having particular reference to the treatment of the pre-formed fiber cake; to provide an apparatus wherein provision is made for decreasing the treating time of each step without sacrificing the efficiency of such step or steps; to provide an apparatus for use with fiber cakes wherein the treatment of the cake is carried out by a body of liquid moving along a face of the cake and transversely with respect to an applied centrifugal force; to provide an apparatus for use in the treatment of fiber cakes 45 wherein a flow of liquid takes place lengthwise or substantially parallel to the axis of the cake while there is a simultaneous flow transversely or radially of the cake; to provide an apparatus for use in the treatment of fiber cakes 50 wherein provision is made for subjecting the cake to a direct and reverse flow of liquid while also maintaining a progressive flow of liquid endwise of the cake; to provide a novel apparatus for forming and treating a fiber cake; to provide an apparatus wherein provision is made for prevent-

ing deforming of a fiber cake during the processing steps; and to provide other improvements as will hereinafter appear.

In the accompanying drawings Fig. 1 represents a sectional elevation of an apparatus embodying one form of the present invention; Fig. 2 represents a plan of the same; Fig. 3 represents a section on line 3—3 of Fig. 1; Fig. 4 represents a sectional elevation of one form of processing receptacle; Fig. 5 represents a sectional elevation 10 of a modified form of the invention; Fig. 6 represents a section on line 6—6 of Fig. 5; Fig. 7 represents a sectional elevation of another form of the invention; Fig. 8 represents a sectional elevation of a further modification of the invention; Fig. 9 represents a section on line 9—9 of Fig. 8; Fig. 10 represents diagrammatically the result of the initial flow of liquid with respect to a fiber cake and in accordance with the present invention; Fig. 11 represents the same showing 20 the liquid partly penetrating the cake; and Fig. 12 represents the same with the penetration completed.

Referring to the drawings one form of the present invention consists of a rotatable receptacle or bucket 10, the inner peripheral face 11 of which is upwardly flared or tapered to conform substantially in size and shape to the outer periphery of the preformed fiber cake 12. Usually these cakes 12 are of annular, truncated shape. 30 The construction, as here shown, is such as to permit the cake 12 to enter the receptacle 10 so that it assumes a predetermined position with its outer periphery flush with the inner face 11 of the receptacle 10. The inner peripheral face 11 35 of the receptacle 10, as here shown, is provided with a plurality of grooves 13 which extend side by side in curved or inclined relation from the lower portion of the receptacle to a point in close proximity to the mouth or open end of the receptacle 40 10. The direction of the incline or curve of these grooves 13 is in the direction to form a path for liquid expelled or discharged by centrifugal force from the cake 12. Thus if the receptacle 10 is arranged to rotate in a counter-clockwise direction, 45 these grooves 13 will leave a common plane near the bottom of the receptacle and curve upwardly and circumferentially to the right as seen in Fig. 4 to terminate in a plane near the top of the receptacle. The upper or outlet ends of the grooves 50 13 not only terminate below the rim of the mouth of the receptacle but in juxtaposed relation to the outer periphery of a cake operatively positioned in the receptacle. The function of this construction is to provide a circumferential es- 55

cape for the liquid discharged from the outer periphery of the cake 12, as otherwise the liquid backing up on this periphery would prevent the necessary leaching from taking place. Furthermore the grooves 13 have the function of causing the liquid to reenter the cake near the upper end thereof and pass through it in a direction reverse to that caused by the centrifugal action. Coaxially located on the bottom of the receptacle 10 is a hub 14 which is made fast in any suitable manner to a driven shaft 15 operatively associated with any suitable source of power.

For supporting the cake 12 in the receptacle 10, an annular plate 16 is mounted in the receptacle in spaced relation to the bottom thereof by means of spacer blocks 17 and screws 18 or like fastening devices passing through the bottom of the receptacle and entering the plate 16. The diameter of the plate 16 is such as to fit snugly at its designed location within the receptacle 10. A liquid supply pipe 19 is made fast at its lower end in the aperture of the plate 16 and rises coaxially within the receptacle 10 to project above the top thereof. This construction provides a passage for entering liquid downwardly through the pipe 19 into the space 20, and then outwardly or radially to the inner wall of the receptacle where, as here shown, it has an escape by way of a plurality of substantially vertically disposed passages 21 through the plate 16. That circumferential portion of the plate 16 which is provided with the passages 21 has a width substantially equal to the thickness of the cake 12 so that the discharge ends of the passages 21 will be juxtaposed with respect to the bottom annular face of the cake 12 when the latter is in treating position.

For retaining the cake 12 in this position upon the plate 16 within the receptacle 10, a cover plate 22 is provided which is apertured to fit over the pipe 19 and seats on a circumferential shoulder 23 formed by the top flange 24 of the receptacle 10. As here shown, this cover plate 22 is made fast by screws 25 to a core 26 which fits about the pipe 19 and has its outer surface tapered to conform to the inner surface of the cake 12. The tapering diameter, however, of this core 26 is such that when the core is in position an annular space 27 will be formed between it and the opposed face of the cake 12 so that treating liquid discharged from the passages 21 will have a relatively restricted channel for flow along that face of the cake.

In order that the treating liquid or wash water flowing upwardly through the cake 12 and discharging from the passages 21 may have a suitable escape to the exterior of the receptacle, circumferentially arranged rows of openings or slots 28 are provided through the plate 22 and are so located that their inlet ends are in abutting relation to the upper face of the cake 12. Also it will be noted that these openings or slots 28 are positioned closer to the inner periphery of the cake 12 than to the outer periphery thereof in order not to prematurely release the reverse flow of the treating liquid from the outer side of the cake to the inner side.

In the form of the invention here illustrated the rows of openings 28 are radially arranged circumferentially around the plate 22, and preferably the outermost opening of each row is of larger diameter than the innermost opening. This provides for a restricted discharge where there is a maximum volume of flowing liquid so that a larger portion of it is diverted and caused

to repass through the cake to exit through the largest discharge openings.

A collar 30 is arranged to fit over the projecting end of the pipe 19 and is fixed in flush relation against the cover plate 22 by means of a set screw 31 or the like.

In the form of the invention shown in Figs. 5 and 6 the receptacle 32 in which the treating operations take place is substantially identical in construction with the receptacle 10 shown in the former figures though in this instance its upper circumferential edge is threaded as shown at 33 for the purpose of receiving a fastening ring 34.

In this form of the invention the cake 35 is fitted with a core 36, after it has been formed in the spinning bucket, and the outer circumference of this core is tapered to conform to the inner periphery of the cake though of slightly less diameter throughout its length in order to have a loose fit within the cake. This loose fit provides for an annular chamber 37 corresponding in function to the chamber 27 in the construction shown in Fig. 1. One end of the core 36 is preferably formed with a flange 38 which serves as a support for the cake when transferring it from the spinning bucket to the processing receptacle 32. This flange 38 is provided with rows of perforations 40 which open at one end against the juxtaposed face of the cake and at the other end communicate with the atmosphere through the aperture of the ring 34. For transferring the cake 35 and its core 36 from the spinning bucket to the receptacle 32, a tubular stem 41 is provided of a shape and size such as to pass readily through the axial opening of the core 36. As a part of this stem 41, a flange 42 is provided of such a diameter as to seat against the opposite face of the cake from that with which the flange 38 contacts. Circumferentially disposed about the inner portion of this flange 42 are one or more rows of perforations 43 so arranged as to open against the end of the seated cake 35. The diameter of the flange 42 is also such as to fit snugly within the receptacle 32 and form a false bottom therefor which is supported in spaced relation to the bottom of the receptacle by means of an annular shoulder 44 or any other suitable spacing means. Thus when the stem 41 and its flange 42 is within the receptacle 32, it provides a space 45 which communicates with the bore 46 and also with the perforations 43. In connection with the stem 41 it should be noted that this extends well through the core 36 in order to form a handle or gripping member 47 by which the cake and its supporting parts can be taken from one place to another. Thus it will be seen from Fig. 5 that the core 36, in assembled condition, is in an inverted position with respect to its initial position within the cake and its flange 38 therefore forms a top or cover for the receptacle 30 being arranged to seat on an annular shoulder 50 formed in the upper rim of the receptacle. When in this position the clamping ring 34 can be screwed into position and thus hold the parts during the processing operations.

In the form of the invention shown in Fig. 7 the supporting core and flange stem part is similarly arranged as described in connection with Fig. 5, but in this instance a supplemental sleeve 51 is provided to serve as the initial core or supporting means for the cake 35. It will be understood that the core 36, above described, is somewhat reduced in diameter to allow the sleeve 51 to fit over it when it is placed thereon with its

fiber cake in place. This sleeve 51 is tapered to conform to the tapered opening of the fiber cake but is of somewhat smaller diameter in order to have a loose fit thereon and provide an 5 annular chamber 52 between the cake and the sleeve through which the treating liquid rises freely to travel along the inner periphery of the cake. Also it is preferable to provide this sleeve 51 with radially disposed holes 53 which are arranged to open against the inner periphery of the cake to serve as passages for a drying medium when the core 36 is removed therefrom.

In the form of the invention shown in Figs. 8 and 9 a construction is shown which includes a 15 novel and original device for use as an adjunct of the spinning operation which forms the fiber cake. This device, as here shown, consists of a cup 60 having an annular bottom 61 and is of a size suitable to fit within the usual type of 20 processing receptacle 62. The contour of the cup 60 corresponds generally to the shape which the formed fiber cake is to assume and when the cup 60 is located within the ordinary spinning bucket the fiber filaments are spun directly into it instead of into the bucket as in the usual practice. When the cake is formed and has been removed in the cup 60 from the bucket, the cup and its 25 contained cake are inserted within the receptacle 62 for the processing steps. In carrying out this 30 portion of the cake treating it has been found desirable in the present novel method to provide an annular space 63 between the outer wall of the cup 60 and the inner wall of the receptacle 62. To that end the upper circumferential edge 35 64 of the cup is of greater diameter than the correspondingly downwardly tapered edge so that the latter is spaced from the receptacle 62 throughout its length. In order that this spacing may be properly formed the lower circumferential 40 edge 65 of the cup 60 is of step formation to conform to the configuration of a stepped ring 66 which is located within and fits about the bottom corner of the receptacle 62. The edge 65 then seats in the ring 66 so that the annular chamber 45 63 is provided which is closed at its top and bottom.

For the purpose of permitting the treating liquid to enter the cake 35, a tubular core 67 is provided of a size to fit loosely within the opening 50 of the cake 60, so that its lower end seats against the flange 61. This construction provides a passage 68 axially through the core 67 and communicating with the space 70 formed between the bottom 61 of the cup 60 and the receptacle 62. 55 This loose fit of the core 67 in the cake provides the passage 69 along the inner face of the cake by means of which the entering treating liquid finds a path of least resistance to flow around the cake and produce the novel surface treatment of 60 the invention. From this space 70 the treating liquid has free access to the lower or bottom face of the cake 35 by means of ports 71 arranged circumferentially about the bottom 61 in such a position that each opens against this face of the 65 cake. The discharge of this liquid from the cake takes place by way of ports 72 formed in the flange 73 of the core 67, it being observed that the flange 73 also serves as a cover for the cup 62 and seats thereon through the medium of a packing ring 74. An annular clamping ring 75 is arranged for threaded engagement with the rim of the receptacle 62 and serves to hold the core 67 with its flange 73 in place as well as the cake during the processing operations. While 70 75 the general direction of flow of the liquid is up-

wardly and endwise of the cake it is also caused to travel transversely outwardly of the cake due, to the rotation of the receptacle 62 during the processing operation, and therefore it is desirable to relieve any back pressure at the outer periphery of the cake by providing laterally disposed passages 76 through the wall of the cup 60 and communicating with the surrounding passage 63. Also it should be noted that the wall of the receptacle 62 is preferably provided with relief 10 passages 77 near the upper end of the passage 63 and communicating therewith so that any excess liquid will find an escape by way of these passages 15 77.

In the form of the invention shown in Figs. 4 to 9 inclusive, the bucket 10 is provided with a plurality of vanes 78 located on the bottom thereof in a circumferential arrangement between the outlet of the liquid supply bore and the circumferentially arranged passages leading to the bottom of the fiber cake. Each of these vanes is of such a shape as to impel the entering liquid radially outward toward the aforesaid passages and thereby increase its velocity so that it enters the passages with a pressure greater than the 20 normal pressure of the liquid travelling downwardly through the bore. The vanes are so arranged that they strike the liquid the moment it emerges from the liquid supply bore and prior to the time it has any flow by centrifugal force, 25 thus exerting a positive impelling force not dependent upon rapid rotation of the bucket. This increased velocity is an important feature of the invention since it makes it possible to obtain the necessary initial velocity with a relatively low 30 35 rotating speed of the bucket. This low speed of rotation materially reduces the cost of manufacture because parts can be used which ordinarily would not stand the wear and tear of high speed rotation.

Also in conjunction with the aforesaid figures it should be noted that the liquid supply bore, whether it be in a stem as described in connection with Figs. 5 and 7, or in a core as described in conjunction with Fig. 8, is of tapered construction 40 45 with the smaller diameter at the inlet end and the larger diameter at the outlet end. The effect of this taper is to counteract the tendency of the liquid under centrifugal force to back up into the bore and its effect is to produce a reacting 50 force such as will increase the pressure instead of diminishing it as would be the case in a bore of uniform diameter.

In prior apparatus and methods for treating fiber cakes it has been the general practice to 55 force the treating liquid transversely through the cake and as this direction of flow meets the maximum resistance of the cake the complete saturation and treating of the cake requires a considerable period of time. The present invention, however, is distinguished from such prior methods in that the flow of liquid takes place endwise or parallel to the axis of the cake and along a resistance relieving channel and thereby accomplishes what neither the crosswise nor 60 oblique flow of prior methods is possible to obtain in the same period of time. That is to say by an endwise flow the time of properly processing to bring about uniformity of penetration of the cake is approximately cut in half. By 65 70 the provision of the annular passageway along the inner periphery of the cake a line of slight initial resistance is provided which allows the entering liquid to flow freely along this inner face without encountering the direct resistance 75

of the hard cake body and therefore as this face treatment continues the liquid gradually washes its way deeper and deeper into the body. Thus, as will be seen from Fig. 10, the first effect of 5 releasing the liquid against the bottom of the cake is to subject that portion of the cake to the pressure of the incoming liquid and since the cake at this time is in a state of hardness resistant to any flow, the entering liquid naturally 10 seeks the line of least resistance and works its way through the inner bottom corner of the cake to the passage. It then rises to leach or treat the inner cake face and when the liquid reaches the top of the cake it forces its way 15 laterally outward across the inner upper corner to the discharge passages. This travel is illustrated in Fig. 10 and shows a cake after one minute's treatment by the present apparatus and method. With a continued flow of the liquid 20 endwise of the cake and subject to the centrifugal action these treated corner areas increase in size while the surface leaching or treating extends deeper into the cake until after some three minutes of treatment the cake will appear 25 as shown in Fig. 11. Finally the areas have extended until the entire cake is saturated as shown in Fig. 12 which is the result of eight minutes treatment by the present apparatus. Thus at 30 all times after the preliminary steps the cake is completely submerged in a body of liquid moving progressively upwardly and inwardly of the cake toward the discharge outlets to quickly and effectively wash or treat the cake in the desired manner. It should be noted also that the grooves 35 in the inner wall of the receptacle serve to relieve back pressure which would otherwise exist at the outer periphery of the cake and this liquid entering the grooves travels upwardly to discharge against the upper portion of the outer face of the cake and flow inwardly across the 40 body to the outlet passages.

It will now be apparent that a simple and efficient apparatus has been devised for processing fiber cakes and wherein the cake is subjected to 45 the flow of liquid under pressure endwise through and around the cake so that the washing or treating takes place in a progressive manner. It should also be noted by this improved apparatus and method that the cake is subjected to pressure on all sides during treatment by reason of the fact that it is submerged in the liquid and while so submerged is subjected to a rotating action. Furthermore the outer or normally exposed face of the cake is confined in a retaining wall during the processing operations so that the 50 fibers are prevented from displacement by the liquid pressure.

While in the foregoing the term "fiber cake" 55 has been used as the material treated it is to be understood this is used in a generic sense and that the various materials in other forms can be successfully processed by the present invention.

While only four forms are here shown in which 60 this invention may be embodied, it is to be understood that the present invention is not limited to any specific construction but might be applied to various forms without departing from the spirit of the invention or the scope of the appended claims.

Having thus described our invention, we claim:—

1. An apparatus for treating fiber cakes comprising a rotatable receptacle for receiving a 75 fiber cake, means to cause an endwise flow of

liquid through said cake, and means to rotate said receptacle to cause a transverse flow of liquid in said cake.

2. An apparatus for treating fiber cakes comprising a support for a fiber cake, a circumferential wall encircling the outer periphery of said cake, a circumferential imperforate wall encircled by the inner periphery of said cake, said walls forming a passage for liquid having an inlet at one end of said cake and an outlet at the other end of said cake, means for feeding liquid to the inlet of and through said passage, and means for causing said liquid to flow in an angular direction with respect to its direction of flow through said passages. 15

3. An apparatus for treating fiber cakes comprising a support for a fiber cake, a circumferential wall encircling and in contact with the outer periphery of said cake, a circumferential imperforate wall encircled by the inner periphery of said cake but spaced therefrom, said walls forming a passage for liquid having an inlet at one end of said cake and an outlet at the other end of said cake, means for feeding liquid to the inlet of and through said passage, and means to 25 rotate said cake while said liquid is travelling endwise therethrough.

4. An apparatus for treating fiber cakes comprising a support for a fiber cake, a circumferential wall encircling the outer periphery of said 30 cake having grooves therein juxtaposed with respect to said cake, a circumferential imperforate wall encircled by the inner periphery of said cake, said walls forming a passage for liquid having an inlet at one end of said cake and an outlet at the other end of said cake, and means for feeding liquid to the inlet of and through 35 said passage.

5. An apparatus for treating fiber cakes comprising a rotatable receptacle adapted to receive a fiber cake endwise therein, a circumferential imperforate wall encircled by the inner periphery of the cake and forming a passage for liquid between said wall and the receptacle, an annular member supporting said cake in said passage, 45 means to support said member to form a chamber in the bottom of said receptacle, said member having openings leading from said chamber to the bottom of said cake, and means for causing a flow of liquid into said chamber and through 50 said openings to pass endwise through said cake in said passage.

6. An apparatus for treating fiber cakes comprising a rotatable receptacle adapted to receive a fiber cake endwise therein, a circumferential 55 imperforate wall encircled by the inner periphery of the cake and forming a passage for liquid between said wall and the receptacle, an annular member supporting said cake in said passage, means to support said member to form a chamber 60 in the bottom of said receptacle, said member having openings leading from said chamber to the bottom of said cake, means for causing a flow of liquid into said chamber and through said openings to pass endwise through said cake in said 65 passage, and means to rotate said receptacle during the flow of liquid through said chamber.

7. An apparatus for treating fiber cakes comprising a rotatable receptacle adapted to receive a fiber cake endwise therein, a circumferential 70 imperforate wall encircled by the inner periphery of the cake and forming a passage for liquid between said wall and the receptacle, an annular member supporting said cake in said passage, means to support said member to form a chamber 75

in the bottom of said receptacle, said member having openings leading from said chamber to the bottom of said cake, means for causing a flow of liquid into said chamber and through said openings to pass endwise through and around said cake in said passage, and means to prevent endwise movement of said cake during said flow of liquid.

8. An apparatus for treating fiber cakes comprising a rotatable receptacle, an annular member supporting said cake in endwise position in said receptacle, means to support said member to form a chamber in the bottom of said receptacle, said member having openings leading from said chamber, to the bottom of said cake, means including an outwardly tapered bore for causing a flow of liquid into said chamber, impeller vanes in the path of said liquid, and means to rotate said receptacle.

20 9. An apparatus for treating fiber cakes comprising a sleeve arranged to fit within a preformed cake, a stem passing through said sleeve having a flange seating against an end of said cake, said flange having passages therethrough opening against said cake, a receptacle, means in said receptacle for supporting said flange in spaced relation from the bottom thereof and so that the wall of said receptacle encircles said cake, a cover for said receptacle having passages opening in juxtaposed relation to the end of said cake, and means to conduct liquid through said stem to the inlets of said flange passages.

10. An apparatus for treating fiber cakes comprising a sleeve arranged to fit within a preformed cake, a stem passing through said sleeve having a flange seating against an end of said cake, said flange having passages therethrough opening against said cake, a receptacle, means in said receptacle for supporting said flange in spaced relation from the bottom thereof and so that the wall of said receptacle encircles said cake, a cover for said receptacle having passages opening in juxtaposed relation to the end of said cake, means to conduct liquid through said stem to the inlets of said flange passages, and means to rotate said receptacle.

11. An apparatus for treating fiber cakes comprising a perforated sleeve arranged to fit within a preformed cake, a core passing through said sleeve and arranged to cover the perforations in said sleeve, a flange on said core seating against an end of said cake, said flange having passages therethrough opening against said cake, a tubular stem extending through said core, a flange on said stem having passages in juxtaposed relation to the bottom of said cake, a receptacle, and means in said receptacle for supporting said tubular stem spaced from the bottom of said receptacle, whereby liquid entering through said stem has access to said bottom flange passages.

60 12. An apparatus for treating fiber cakes comprising a perforated sleeve arranged to fit within a preformed cake, a core passing through said sleeve and arranged to cover the perforations in said sleeve, a flange on said core seating against an end of said cake, said flange having passages

therethrough opening against said cake, a tubular stem extending through said core, a flange on said stem having passages in juxtaposed relation to the bottom of said cake, a receptacle, means in said receptacle for supporting said tubular stem spaced from the bottom of said receptacle, whereby liquid entering through said stem has access to said bottom flange passages, and means to rotate said receptacle.

13. An apparatus for treating fiber cakes comprising a sleeve arranged to fit within a preformed cake, a core passing through said sleeve having a flange seating against an end of said cake, said flange having passages therethrough opening against said cake, a receptacle having grooves on the inner wall thereof, means in said receptacle for supporting said flange in spaced relation from the bottom thereof and so that the wall of said receptacle encircles said cake, a cover for said receptacle having passages opening in juxtaposed relation to the end of said cake, and means to conduct liquid through said core to the inlets of said flange passages.

14. An apparatus for treating fiber cakes comprising a sleeve arranged to fit within a preformed cake, a core passing through said sleeve having a flange seating against an end of said cake, said flange having passages therethrough opening against said cake, a receptacle having grooves on the inner wall thereof, means in said receptacle for supporting said flange in spaced relation from the bottom thereof and so that the wall of said receptacle encircles said cake, a cover for said receptacle having passages opening in juxtaposed relation to the end of said cake, means to conduct liquid through said core to the inlets of said flange passages, and means to rotate said receptacle.

15. In an apparatus for processing fiber cakes, the combination of a receptacle, a device for supporting a fiber cake in said receptacle, means forming with the inner face of said cake a passage lengthwise of said cake, means for delivering a supply of liquid to the bottom of said cake to maintain a flow through said cake and passage, cover means forming discharge passages communicating with the upper end of said cake, and means to rotate said receptacle.

16. An apparatus for treating fiber cakes comprising a support for a fiber cake, a receptacle encircling said cake, means to space said cake support from the bottom of said receptacle, impeller vanes in said space, a member having a bore for delivering liquid to said space, and means for rotating said receptacle.

17. An apparatus for treating fiber cakes comprising a support for a fiber cake, a receptacle encircling said cake, means to space said cake support from the bottom of said receptacle, impeller vanes in said space, a member having a bore increasing in diameter toward said space, and means for rotating said receptacle.
